UNITED STATES PATENT OFFICE.

LEON W. SCHUMANN, OF ROCHESTER, NEW YORK, ASSIGNOR, BY MESNE ASSIGNMENTS, TO THE G. R. S. PRODUCTS, INC., OF COLONIE, NEW YORK, A CORPORATION OF NEW YORK.

WASHING MACHINE.

Application filed March 27, 1922. Serial No. 546,984.

To all whom it may concern:

Be it known that I, LEON W. SCHUMANN, a citizen of the United States of America, residing at Rochester, in the county of Monroe and State of New York, have invented certain new and useful Improvements in Washing Machines, of which the following is a specification.

This invention relates to washing machines, and particularly to washing machines of the cylinder type.

In washing machines of this type the cylinder is usually mounted for rotation on a horizontal axis, the rotation being either continuously in one direction or oscillatory, dependent upon the particular type of machine. The cylinders are usually perforated and immersed in a container partly filled with water. In washing machines of this type, it is necessary to be able to remove the cylinder from the container for cleaning and other purposes, and therefore the driving means for such a cylinder is preferably made easily detachable. In washing machines of this type, it is also desirable to be able to bring the cylinder into an out-of-driving relation with the driving means without stopping the motion of such driving means.

With these and other considerations in mind, the principal objects and purposes of the present invention are to provide a detachable driving connection for a washing cylinder which is constructed and arranged to serve the double function as a detachable means for permitting the removal of the cylinder from the container, and as a clutch for starting and stopping the cylinder when desired; to construct such a device in a simple and efficient manner which facilitates easy operation and which provides a firm driving connection with the minimum amount of lost motion. More specifically, a pyramid type of clutch is provided between the driving connection and the cylinder, one member of the clutch being movable endwise to engage or disengage the other, a spring pressed thrust bearing being provided to maintain the necessary pressure to keep the clutch members in firm driving relation.

Other objects and purposes of the present invention will appear as the description progresses.

In describing the invention in detail, reference will be made to the accompanying drawings, in which:

Fig. 1 is a vertical longitudinal fragmentary view of a washing machine embodying the present invention;

Fig. 2 is a fragmentary end view of the device illustrated in Fig. 1;

Fig. 3 illustrates a section taken on the line 3—3 of Fig. 1, as viewed in the direction of the arrows;

Fig. 4 illustrates a section taken on the line 4—4 Fig. 1 looking in the direction of the arrows; and

Fig. 5 is a perspective view of the spring used in the spring pressed thrust bearing of the washing cylinder.

In order to explain the nature of the present invention, attention is directed to the accompanying drawings which show the principal operating parts of a typical washing machine comprising a skeleton framework 1 carrying a tub 2, and having a closed cylinder 3 rotatably mounted in the tub. To one end of the washing cylinder 3 is bolted a casting, consisting of a plate 4 having a hollow boss 5. The inside of said boss is shaped like a pyramid, but more specifically comprises a pocket shaped to receive a frustum of a triangular pyramid as provided on the end of the driving shaft 6, the end of the driving shaft being preferably slightly larger than the bottom of said pocket to assure contact between the sides of the pyramid and said pocket.

The shaft 6 is journaled in a mechanism 90 casing 7 supported at three points to the skeleton framework by bolts, as shown. The shaft is preferably provided with a circumferential groove 8 to receive an operating member 9 eccentrically connected to an operating handle 10, whereby the operation of the handle 10 slides the shaft 6 into an out-of-engagement with the cylinder 3.

To the shaft 6 is splined a pinion 11 which operatively engages the teeth of the gear sector 12 journaled on a fixed bearing stud 13. The gear sector 12 has a connecting rod 14 pivotally connected thereto, the other end of said rod being provided with a pin 15 journaled in an eccentrically located hole in the worm wheel 16. In operative relation with the worm wheel 16 is a worm 17 pinned to a vertical shaft 18 journaled in the tubu-

lar extensions 19 of the mechanism casing 7. To the lower end of the shaft 18 is pinned a worm wheel 20, which operatively engages a worm 21 on a shaft 22 directly connected 5 with an electric motor 23. The mechanism casing 7 entirely closes the operating mechanism for driving the washing cylinder, and is packed with a suitable lubricant for constantly lubricating the inter-engaging parts 10 of the operating mechanism.

The mechanism casing is provided with a circular flange 24 extending about the driving shaft 6 into the container 2. A flanged collar 25 having an integral curved shelf 26 15 is bolted about the flange 24 on the inside of the container 2. This flanged collar and shelf are provided with adjusting means to adjust its relation with respect to the driving shaft 6. This adjusting means comprises a set screw 27 having a lock nut 28 for locking the set screw in place. In practice, this shelf is adjusted to an elevation to permit the end of the shaft 6 to enter the pocket in the boss 5 on the end of the cylinder 3. With such adjustment, the shaft 6 20 may be brought into driving relation with the cylinder 3 by operating the handle 10 when the shaft 6 is driven through the driving mechanism by the motor 23.

30 In order to maintain the cylinder in firm driving relation with the shaft 6 through the pyramidal clutch, means for obtaining spring-pressed end thrust is preferably provided. This predetermined relation between 35 the shaft 6 and the cylinder is desirable on account of inaccuracies in manufacture, and other causes, such as distortion caused during shipment, changes in temperature, elongation of the cylinder 3 due to moisture, and 40 the like. It has been found desirable to provide means to take care of such variations, and in the particular embodiment shown the skeleton framework 1 is provided with a cross member 29 of angle iron directly opposite to the shaft 6 and on the outside of the yieldable end wall remote from the mechanism casing of the container 2. Supported on the inside and from the top of the container is a U-shaped bearing member 45 30. The end opposite the clutch of the washing cylinder 3 has a casting bolted thereto, comprising a plate 31 having a boss 32 provided with a journal 33. This journal 33 is adapted to rest in the bearing portion of the 50 55 U-shaped bearing member.

Suitable means are preferably employed to urge the U-shaped bearing member toward the cylinder 3. This means comprises the provision of a spring for urging the U-shaped bearing member against the boss 32, in order to maintain the shaft 6 and the hollowed boss 5 in snug operative engagement. This spring 34 comprises an elongated leaf-spring member bent in the form 60 65 of an arc, as clearly illustrated in Fig. 5.

On the concaved side of this spring member are provided two radially extending ears 35.

In practice, after the washing machine has been assembled, the spring 34 is inserted between the wall of the container 2 and the 70 cross member 29, as clearly illustrated in Fig. 1, thus causing the wall of the container 2 and the U-shaped bearing member to be urged toward the inside of the container, thereby providing the spring thrust bearing 75 desirable for washing machines of this type.

Having thus fully described my invention, what I desire to secure by Letters Patent, is:—

1. In a washing machine, the combination of a cylinder, means adapted to be shifted into driving engagement with one end of said cylinder, and resilient means at the other end of said cylinder for maintaining said cylinder in a predetermined 80 spring-pressed engagement with respect to said last mentioned means.

2. In a washing machine, the combination of a readily removable cylinder having a clutch member at one end, a driving member provided with a companion clutch member, means for engaging and disengaging said members, and means at the other end of said cylinder for maintaining said clutch members in a predetermined spring-pressed 90 relation when engaged.

3. A washing machine comprising, a container, a cylinder removably journaled in said container, shiftable driving means normally out of engagement with said cylinder, means for shifting said driving means into engagement with one end of said cylinder, and means at the other end of said cylinder for maintaining said cylinder and driving means in a predetermined driving relation. 100 105

4. In a washing machine, the combination of a container, a cylinder, journals on opposite ends thereof, one of said journals having a tapered opening therein, means for rotatably supporting said cylinder in said container, shiftable driving means having a tapered end adapted to be shifted into operative engagement with the tapered opening in one of said journals thereby lifting said journal from its support, and means for resiliently urging said journal into engagement with said shiftable means for maintaining a firm operative connection between said driving means and the journal containing said opening. 110 115 120

5. In a washing machine, the combination of a container, a cylinder, journals on opposite ends of said cylinder, means for rotatably supporting said cylinder in said container, shiftable oscillatory driving means having a tapered end adapted to be 125 130

shifted into operative engagement with one of said journals thereby lifting the corresponding end of the cylinder and supporting the same, means for shifting said shiftable means, and resilient means for urging said journal into engagement with said shiftable means, whereby said resilient means maintains the tapered driving means in engagement with said last mentioned journal in spite of the weight of the cylinder tending to disengage them.

6. In a washing machine, the combination of a container having a yieldable wall, a framework for supporting said container, a journal support depending from the top of said container, and means for urging said wall and said journal support inward.

7. In a washing machine, the combina-

tion of a container having a yieldable wall, a framework for supporting said container, a journal support depending from the top of said container and on the inside thereof, one member of said framework re-enforcing said wall, and a spring for urging said wall from said framework.

8. A spring for thrust bearings for cylinder type washing machine comprising, a leaf spring of arcuate shape, and means for supporting said spring in a predetermined relation with respect to such thrust bearings including an ear extending transversely from the concave side of said leaf spring.

In testimony whereof I hereto affix my signature.

LEON W. SCHUMANN.
